UNITED STATES PATENT OFFICE.

OREA M. KELLEY, OF LOWELL, MASSACHUSETTS.

ASSEMBLY-MACHINE.

1,320,238.

Specification of Letters Patent. Patented Oct. 28, 1919.

Application filed March 6, 1918. Serial No. 220,768.

To all whom it may concern:

Be it known that I, OREA M. KELLEY, a citizen of the United States, residing at Lowell, Middlesex county, and State of Massachusetts, have invented and discovered certain new and useful Improvements in Assembly-Machines, of which the following is a specification.

My said invention relates to a method of, and an apparatus for, manufacturing ammunition for fire-arms; and consists in the steps of procedure in the process, and combinations and arrangements of elements in the apparatus, hereinafter described and particularly set forth in the accompanying claims.

The purpose of the invention is to produce slug filled jackets for bullets by a series of operations following each other in definite sequence and order, and in an unbroken arrangement of steps from the initial operation until the finished article is produced.

A further object of the invention is to produce a unitary apparatus or single machine which will form the bullet jackets, fill the same with lead slugs, and then by a series of operations shape the jackets and slugs into integral units and of the size required for inserting in the shells of the cartridges.

In the accompanying drawings forming part of this specification, like characters represent similar parts in the several views shown of which,

Figure 1 is an elevation of a complete machine constructed in accordance with my invention;

Fig. 2 a section on the line 2—2 of Fig. 1; Fig. 3 an elevation of the machine portion shown in Fig. 2;

Fig. 4 a detail section on the line 4—4 of Fig. 2;

Fig. 5 a detail perspective of one of the transfer elements of the device;

Fig. 6 a horizontal section on the line 6—6 of Fig. 1;

Fig. 7 a vertical section on the line 7—7 of Fig. 6;

Fig. 8 a detail section on the line 8—8 of Fig. 1;

Fig. 9 a detail horizontal section on the line 9—9 of Fig. 1, and,

Figs. 10 to 19 show the development of the jackets, and the different steps taken in inserting the slugs in the jackets and fixing the same therein.

The apparatus consists of a platform 15 which is supported upon legs 16 and has mounted thereon the main frame 17 of the machine. The frame 17 carries a super-frame structure 18 which in turn supports a hopper 19 designed to contain the bullet jackets, and a hopper 20 of special construction for holding the molten metal from which the slugs are formed.

The jackets 21 (see Figs. 10 to 19) are fed through the tube 22 with their closed ends leading. The open end 23 of the tube 22 is located in line with a cavity or recess 24 formed between the resilient fingers 24 of a reciprocable transfer block 25 which is of a size to retain only one jacket at a time. These jackets are expelled from the transfer block to a bushing chain in a manner to be described.

The hopper 20 has formed on its under side a cylindrical casing 26 in which is snugly fitted a hollow cylindrical member 27 provided with a series of measuring openings 28 whose capacity may independently be varied by means of an adjusting screw 29 which screws into the opening 28. When in one position, these openings 28 are in communication with the interior of the hopper 20 through the neck 30 thereby permitting a portion of the molten metal in the hopper to flow into and fill each of the measuring openings 28. The cylindrical member 27 is then rotated to bring its openings 28 immediately above and in register with a series of molds 31 which form part of a horizontally disposed mold-carrying chain 32 supported on the driven sprocket 33 and the idle sprocket 34. In detail, this chain 32 consists of a series of cylindrical blocks 35 bored out at 36 and provided with a false bottom 37 integrally formed upon the upper end of a spring-pressed rod 38. The blocks 35 are formed into a continuous chain 39 by a series of links 39 shown in Fig. 6. An intermittent movement is imparted to the

chain through means to be explained. After the molds have been filled they are moved to a position where the slugs 36 formed therein are ejected and deposited in a series of chutes leading to the bushing chain.

The manner of transferring the slugs from the mold carrying chain to the chutes is accomplished in the following manner: A continuously driven shaft 40 is journaled 10 in suitable bearings 41 on the frame 17 and has keyed thereto a single throw cam 42 which operates to lift a roller 43 journaled in the end of the arm 44 on a shaft 45 that is mounted to oscillate in bearings secured 15 to the frame 17. This shaft 45 carries a pair of arms 46 connected at their outer ends by a curved plate 146 of a length sufficient to operate beneath five of the rods 38. The lifting of these rods together with 20 the members 37 pushes the several slugs up into a series of spring bushings 47 each of which is composed of two members 48 held together by a pair of springs 49. This structure of bushing thereby automatically 25 adjusts itself to any slight variation in the sizes of the slugs. The members 48 of each bushing are loosely supported by two plates 50 which are secured to opposite surfaces of a block 51 that is slidably mounted in 30 a casing 52 secured to the top of the frame 17. A depending and slotted lug 53 is mounted on the under side of each block 51 and has pivoted connection with the upper end of a lever 54 fulcrumed at 55 to a bracket formed on the frame 17. The 35 lower end of said lever 54 carries a roller 55 which is in contact with the cam 42 at a point approximately 90 degrees in advance of the roller 43. A spring 56 tends to normally hold the roller 55 in contact with the cam 42. Mounted in bearings 57 formed on the block 51 is a rocker shaft 58 provided with a series of upwardly and outwardly inclined arms 59, retained in such 40 position by means of springs 60, and said arms are turned down at their outer ends to form push members 61 for ejecting the slugs from the bushings. This ejection of the slugs is accomplished by means of a rearwardly extending arm portion 62 that is secured to the rocker shaft and provided with a downwardly turned end 63 that acts as a cam element and is adapted to come into contact with the upper rear edge of the casing 52 when the block 51 is moved forward, thereby causing the several forward ends 61 to enter the bushings and eject the slugs 45 into the chutes 64 which merge into a common chute 65.

50 It will be noted that as five slugs are deposited at one time it is necessary to have the chutes 64 of different lengths to prevent jamming or crowding of the slugs when entering the single chute 65. The slugs 136 65 are therefore caused to pass in single file

down the chute 65 and enter a transfer device of the same construction as that located at the end of the chute 22, namely a pair of spring fingers 66 on a transfer block 67 which is of a size to retain only one slug 70 at a time. Both transfer devices are designed so that when they are moved away from their respective chutes, the sides of the blocks 25 and 67 are so positioned that they retain the second jacket or slug while 75 holding the first one in position to be entered into the bushing chain that operates in connection with the shaping and sizing dies.

The bushing chain comprises a series of 80 cylindrical blocks 68 connected to each other by pairs of links 69 to form an endless chain. Each of the blocks 68 has a central bore 70 in which are mounted a series of bow springs 71 provided respectively with a 85 shoulder or stop 72 to prevent the return passage of a jacket. Mounted in an upstanding bracket 73 secured to the platform 15 are two stub shafts 74 and 75 on which are loosely mounted a driven sprocket 76 90 and an idle sprocket 77 which carry the bushing chain. During the intermittent movement of this chain, its downward traveling portion passes in alignment with a series of dies formed in a vertical member 95 78 secured to the platform 15.

The frame 17 is provided with a pair of slideways 79 in which is mounted to reciprocate a cross head 80 carrying a series of die elements 81 adapted to coöperate with 100 the dies 82 formed in the member 78 to form and fill the jackets, as described later. Mounted to reciprocate in slideways 83 secured to the member 78 is a cross head 84 carrying a series of ejecting elements 85 105 which are adapted to enter certain of the dies to dislodge the jackets therefrom.

All of the several elements and devices described are indirectly operated from a main driven shaft 86 mounted on the platform 15. This shaft 86 is driven by any suitable power through the medium of a pulley 88 and belt 89 as shown. Keyed to the shaft 86 is a spur pinion 90 which is in constant mesh with a gear 91 secured to 110 a second shaft 92 journaled in suitable bearings 93. In the device illustrated, these gears operate at a ratio of five to one owing to the fact that five slugs are cut at one time. A bevel pinion 94 is secured to the shaft 120 92 and drives a similar pinion 95 secured at one end of a vertical shaft 96 which has a pinion 97 on its opposite end meshing with a similar pinion on the shaft 40. A chain 98 operating on a sprocket 99 of 125 the shaft 40 and also riding on a sprocket 100 secured to the cylinder 27 causes the cylinder to rotate continuously at a relatively slow speed.

The shaft 92 also has mounted thereon 130

a cam 101 which transmits motion to a bell-crank lever 102 through the medium of a roller 103 on the end of one arm thereof. The other arm of the bell-crank lever has connected to it a pitman 104 which imparts an oscillating motion to an arm 105 fulcrumed on the shaft 106 on which the sprocket 33 is secured. The shaft 106 also carries a ratchet wheel 107 which derives its motion from the arm 105 through the medium of a pawl 108 secured to said arm. The movement of the ratchet and its associated elements imparts the proper movement to the mold chain 32.

15 The crosshead 80 is reciprocated by means of a cam 109 secured to the shaft 86. This cam operates against a roller 110 mounted on a rod 111 that is secured at one end to the crosshead 80 and which is provided at its opposite end with an elongated guide opening 112 through which the shaft 86 projects. Springs 113 tend to normally hold the crosshead in its retracted position. The crosshead 84 is similarly operated to 20 reciprocate in the slideways 83 by means of the same cam 109 operating against a roller 114 mounted in the end of a lever 115 fulcrumed on the frame 17. A pitman 116 connects the lever 115 with one arm of a 25 bell-crank lever 117 mounted beneath the platform 15, and said bell-crank lever transmits a rocking motion to a lever 118 by means of a connecting rod 119. The upper end of the lever 118 is connected to the crosshead 84 through a short pitman 30 120, and springs 121 normally bent to hold the crosshead 84 in its retracted position.

The bushing chain referred to is advanced intermittently to permit of the transferring 35 of the jackets from one die to the next until the entire nine operations are completed. This operation is accomplished in the following manner: The shaft 74 is provided with a ratchet wheel 122 and also has fulcrumed thereon, adjacent the wheel, an arm 123 which carries a spring pressed pawl 124 (see Figs. 1 and 8) which acts against the ratchet wheel 122. An intermittent motion is imparted to the arm 123 by means 40 of a bell crank lever 125 which is fulcrumed on the upper slideway 83 and which has a swivel connection with the arm and a sliding engagement with a pin 126 carried by the crosshead 84. The transfer devices described operate simultaneously and are 45 therefore connected by means of a member 127 which is provided on one surface with a pair of ears 128 carrying a pin 129 to which is loosely connected one arm of a bell-crank lever 130 mounted on a bracket 131 secured to the upright 73. The other arm of the bell-crank is connected to the crosshead 84 by a connecting rod 132. It will be understood that both the intermittent 50 movement of the bushing chain and the

operation of the transfer devices are accomplished during the return stroke of the crosshead 84.

The operation of the device is as follows: 55 Jackets in the form shown (see Fig. 10) 70 are placed in the hopper 19 and fed singly down through the tube 22 to the spring arms 24. The uppermost or first of the plungers 81 now pushes the jacket into the bushing chain which is then advanced one 75 space to place the jacket in position to be inserted into the first of a series of four shaping dies. The jacket is ejected from the first three of these dies by means of the push rods 85, but is withdrawn from 80 the fourth die by means of a series of small projections or burs on the corresponding member 81. These projections bind tightly against the inner surface of the jacket and cause the jacket to be withdrawn from the die and reenter the bushing until the flat end strikes against the shoulders or stops 85 72 which thereby withholds the same in the bushings. At this point, the jacket has been formed completely and it is here that the operation of inserting the slug takes place.

The hopper 20 containing the molten lead is designed to deposit a small portion of its contents into the pockets 28 of the measuring cylinder 27 which is continuously rotating. At the proper time the material in the pockets 28 is emptied into the several molds 36 of the mold chain 31 which carries it to the chutes 64. In order to have 95 the slugs delivered to the chutes in the right position, the following system is used: The action of the plate 146 against the rods 38 causes the slugs to be pushed up into the bushings 47 which, through the action of the 100 cam 42 and lever 54, are moved to overlie the several chutes 64. Immediately upon reaching this position the slugs are forced 105 out of the bushings and caused to drop into the chutes by means of the downturned portions 61 of the levers 59. The slugs then pass down through the chutes 65 and successively into the transferring device. After the forward operation of the transferring device 66 the corresponding plunger 115 110 81 moves the slug into the completed jacket and continues this movement until it has firmly jammed the slug into the jacket in the die member. The bullet is then forced back into the bushing chain by means of 120 the injecting plunger 85 whence it is transferred to the next die by means of a plunger that bevels or crimps the end of the jacket inwardly toward the end of the slug. The two operations following serve to complete 125 the process of shaping the end of the jacket, thereby sealing the slug firmly within. The last plunger simply carries the bullet through the sizing die that trims off any surplus metal. The finished bullet 130

then falls into a drawer or receptacle as indicated.

It is obvious that those skilled in the art may vary the details of construction and arrangement of parts without departing from the spirit of my invention and I therefore do not wish to be limited to such features except as may be required by the claims.

Having thus fully described my said invention what I claim as new and desire to secure by Letters Patent is:

1. In an apparatus for producing cartridge bullets the combination of means for shaping the bullet jackets, means for forming the jacket slugs, and means for inserting and fixing said slugs in the jackets, substantially as set forth.

2. In an apparatus for producing cartridge bullets the combination of means for shaping the bullet jackets in a series of operations, means for molding the jacket slugs, and means for inserting and fixing the molded slugs in the jackets, substantially as set forth.

3. In an apparatus for producing cartridge bullets the combination of a means for shaping the bullet jackets in a series of intermittent operations, means for molding the jacket slugs, and means for inserting and fixing the molded slugs in the jackets in a series of intermittent operations, substantially as set forth.

4. In an apparatus for producing cartridge bullets the combination of a plurality of die elements for successively shaping the bullet jackets, means for molding the bullet slugs, means for assembling the slugs and jackets, a plurality of die elements for fixing the slugs in the jackets, and transferring means for carrying the bullet parts and the bullets between said die elements, substantially as set forth.

5. In an apparatus for producing cartridge bullets the combination of a plurality of die elements for successively shaping the bullet jackets, means for molding the bullet slugs, means for assembling the slugs and jackets, a plurality of die elements for fixing the slugs in the jackets in successive steps, and a chain carrier movable between said die elements and coöperable therewith for transferring the articles between the different die elements, substantially as set forth.

6. In an apparatus for producing cartridge bullets the combination of a plurality of fixed die elements for the bullet jackets, movable die elements coöperable with the fixed die elements, means for ejecting the jackets from said fixed die elements, a carrier for intermittently transferring the jackets to the respective dies, means for molding the bullet slugs, die elements for assembling the jackets and slugs, a plurality of fixed and movable die elements for forming and

fixing the assembled jackets and slugs, said carriers operable to transfer the articles between said second series of die elements; and a common operating means for said molding apparatus, the die elements, and said transferring means, substantially as set forth.

7. In an apparatus for producing cartridge bullets the combination of a plurality of fixed die elements for the bullet jackets, movable die elements coöperable with the fixed die elements, means for ejecting the partially formed bullet jackets, a fixed and a movable die element for finally forming the jackets, said movable finished die element having means for withdrawing the finally formed jackets, means for molding the bullet slugs and applying and affixing the same to said jackets, transferring means for the articles intermittently operable between the die elements, and a common operating means for said die molding apparatus, the die elements, and said transferring means, substantially as set forth.

8. In an apparatus for producing cartridge bullets the combination of a retort for molten metal, a die coöperable with the retort to form the bullet slugs, means for ejecting the formed slugs from the die, means for transferring the ejected slugs, a chute adapted to receive the ejected slugs, and means for applying and fixing the slugs to the bullet jackets, substantially as set forth.

9. In an apparatus for producing cartridge bullets the combination of a retort for molten metal, a series of dies coöperable with the retort to form the bullet slugs, means for simultaneously ejecting the formed slugs from the series of dies, means for simultaneously transferring the ejected slugs, a plurality of chutes adapted to receive the ejected slugs and convey the same in succession to a common discharge point, and means for applying and affixing the slugs to the bullet jackets, substantially as set forth.

10. In an apparatus for producing cartridge bullets the combination of a retort for molten metal, a carrying chain having a plurality of dies coöperable in series with the retort to form the bullet slugs, means for ejecting the series of slugs simultaneously from the carrying chain dies, means for simultaneously transferring the ejected series of slugs, a plurality of chutes of relatively different lengths adapted to receive the ejected series of slugs and convey the same to a common discharge point, a means for applying and fixing the slugs to the bullet jackets, substantially as set forth.

11. In an apparatus for producing cartridge bullets the combination of a receptacle for containing the blank bullet jackets, an intermittently operated chain conveyer

- adapted to receive said jackets, a series of fixed and movable dies coöperable with the chain conveyer to form the jackets to receive the slugs, a fixed finishing die element, a movable die element coöperable therewith to feed the jacket thereto and withdraw the same, and means for applying and fixing the slugs to the jackets, substantially as set forth. 5
12. In an apparatus for producing cartridge bullets the combination of a retort for molten metal, molds for forming the bullet slugs, an intermittently operated chain conveyer adapted to hold the bullet jackets to receive said slugs, a series of fixed and movable dies coöperable with the chain conveyer to shape and fix the assembled slugs and jackets, and means for ejecting the finished bullets from the conveyer, substantially as set forth. 10
13. In an apparatus for producing cartridge bullets the combination of fixed and movable die elements for forming, assem- 15
- bling, and fixing the bullet jackets and slugs, and a chain conveyer coöperable therewith comprising a plurality of cylindrical blocks having openings, and low springs fixed therein adapted to hold the bullet parts, substantially as set forth. 20
14. In an apparatus for producing cartridge bullets, the combination of intermittently operable slug molding means, intermittently operable jacket forming means, intermittently operable means for fixing the slugs in the jackets, and common mechanism for operating all of said means, substantially as set forth. 25

In witness whereof I have hereunto set my hand and seal at Lowell, Massachusetts, this 28th day of February, A. D. nineteen hundred and eighteen. 30
